(57) CLAIM

The ornamental design for a front of a paintball player figurine, as shown and described.

DESCRIPTION

FIG. 1 is a perspective view of a first embodiment of a front of a paintball player figurine showing my new design; and, FIG. 2 is a perspective view of a second embodiment of the front of a paintball player figurine.

The broken line showing of the gun and the belt in FIGS. 1 and 2 is for illustrative purposes only and forms no part of the claimed design.
